UNITED STATES PATENT OFFICE.

FREDRICK J. SHELDON, OF LONGWOOD, WISCONSIN.

GATE-HANGING.

SPECIFICATION forming part of Letters Patent No. 247,697, dated September 27, 1881.

Application filed July 18, 1881. (No model.)

To all whom it may concern:

Be it known that I, FREDRICK J. SHELDON, a citizen of the United States of America, residing at Longwood, in the county of Clark 5 and State of Wisconsin, have invented certain new and useful Improvements in Gate-Hangings; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 My invention relates to gates, and its object is to furnish a swinging gate that will be self-shutting, will swing both ways, is simple of construction, and of satisfactory operation.

In the drawings, Figure 1 is a side elevation 20 of my gate; and Figs. 2 and 3 are views of the swinging device.

A is the gate. It swings between the posts 25 a a, the pivot-post being the longest, and is provided with suitable braces and latch, as shown. To the inside of the pivot-post a is fastened the bracket b. It has arms b³ and cross-bar b², which operate to hold the post c in position within the bracket. It is also provided 30 with the lugs b⁴, to which are secured the ends of the chain b', as shown.

The bottom of the turning-post c rests upon and is pivoted to the bottom brace of the post-frame, and is inclosed near its top by the bracket b, as shown. Secured to lugs on each

side of the bracket is the chain or rope b'. It 35 is given one or more turns around the turning-post, and to prevent slipping it is tacked to the back of the turning-post by a nail or some other simple method.

In the operation of the gate, when it is opened 40 the top of the turning-post will be drawn by the chain b' in the opposite direction to which the gate is swung, while the bottom will remain fixed upon its pivot. The swinging post d will be elevated and inclined toward the latch-post 45 a, so that, according to the laws of gravitation, when the gate is released it will immediately swing back between the posts a a.

Attached to the swinging post d by suitable 50 clamps is the rod e, bent into a handle at the top, and which, when the gate is open, may be pushed into the ground to hold it in place. It is prevented from sinking too deep by the pins e', and when not in use is held up out of the way by the pins e'', as shown.

What I claim as new, and desire to secure by 55 Letters Patent, is—

In a swinging gate, the bracket b, constructed with arms b³, cross-bar b², and having the chain b' secured to lugs b⁴, operating in combination 60 with the post c, substantially as set forth.

In testimony whereof I affix my signature in presence of two witnesses.

FREDRICK J. SHELDON.
